UNITED STATES PATENT OFFICE.

FRANZ O. MATTHIESSEN, OF IRVINGTON, NEW YORK, AND EDWARD E. QUIMBY, OF ORANGE, NEW JERSEY, ASSIGNORS TO THE F. O. MATTHIESSEN & WIECHERS SUGAR REFINING COMPANY, OF JERSEY CITY, NEW JERSEY.

APPARATUS FOR DECOLORIZING SACCHARINE AND OTHER LIQUIDS BY FILTRATION THROUGH BONE-BLACK.

SPECIFICATION forming part of Letters Patent No. 329,330, dated October 27, 1885.

Application filed June 1, 1885. Serial No. 167,206. (No model.)

To all whom it may concern:

Be it known that we, FRANZ O. MATTHIESSEN, of Irvington, New York, and EDWARD E. QUIMBY, of Orange, New Jersey, have invented certain Improvements in Apparatus for Decolorizing Saccharine and other Liquors by Filtration through Bone-Black, of which the following is a specification.

These improvements are especially useful in the class of filters in which sugar-liquor is decolorized by causing it to filter upward through a mass of bone-black contained in the lower portion of a vertical cylinder which is filled with bone-black above the level at which the sugar-liquor is withdrawn, so that the portion of the bone-black by which the filtering operation is performed is compressed by the weight of the column of bone-black above it.

The object of the invention is to effect the uniform removal of the sugar-liquor, as well from the central portion of the column of bone-black as from the outer portions thereof; and to this end the invention consists in the arrangement, at the level at which the sugar-liquor is to be discharged, of transverse troughs protected above by inverted-V-shaped shields, and, if need be, by sieves interposed between the wings of the shields, whereby the bone-black is prevented from making its way into the draining-troughs.

Another feature of the improvement consists in connecting the draining-troughs with the apertures in the side walls of the filtering-chamber, through which the sugar-liquor is discharged by means of horizontal tubes of suitable length, in order that such portion of the sugar-liquor as makes its way upward along the interior surface of the wall of the filter may not have immediate access to the draining-troughs, but be compelled to move laterally a short distance in order to reach a point at which it can make its way into the draining-troughs, the reason for this being that the sugar-liquor rises more freely along the wall of the filter than it does through the central portion of the mass of bone-black. There is less resistance to the upward move-

ment of the sugar-liquor along the wall of the filtering-cylinder than there is in the center of the mass of bone-black, and this feature of the improvement is intended to add such a degree of obstruction to the discharge of the sugar-liquor from the surface of the column of bone-black as will make the total resistance to the movement of the sugar-liquor around the outside of the mass of bone-black equal to the resistance to the upward movement of the sugar-liquor through the center of the mass of bone-black.

Our invention also includes devices for adjusting the height of the column of sugar-liquor which flows into the apparatus, and thereby regulating the degree of hydrostatic pressure under which the sugar-liquor is forced upward through the filtering-chamber.

Our invention may be applied to bone-black filters of a variety of types, as well to those in which the bone-black through which the sugar-liquor is filtered is compressed by the weight of a column of superincumbent bone-black as to those in which the compression is effected by a screw-compressor.

The accompanying drawings of a filtering apparatus containing our improvements are as follows:

Figure 1 is a central vertical section, showing the filtering-chamber surmounting a receiving-chamber for receiving the exhausted bone-black discharged from the bottom of the filtering-chamber and conducting it to the bottom of a well, from which it is elevated by means of a chain and bucket or other elevator. Fig. 2 is a horizontal section through the line *x* *x* on Fig. 1. Fig. 3 is a horizontal section through the line *y* *y* on Fig. 1. Fig. 4 is a central vertical section similar to Fig. 1, with the exceptions that the drain-troughs are not represented in transverse section, as in Fig. 1, but one of the drain-troughs is shown in central longitudinal section, and the compressor, which is shown in Fig. 1, is omitted. Fig. 5 is an elevation of the upper part of the filtering-chamber and well, showing the cistern which supplies sugar-liquor to the apparatus in cen-

tral vertical section. Fig. 6 is an isometrical perspective of the end portion of one of the troughs *h*, and portions of its shield, &c. Fig. 7 is a transverse vertical section of one of the troughs *h* and its shield.

The apparatus represented in the drawings consists, substantially, of a vertical cylinder, *A*, containing a column of bone-black, *B*, supported at the bottom upon a suitable valve or 10 perforated diaphragm, *C*, for gradually discharging the exhausted bone-black from the bottom *b* of the column of bone-black. The exhausted bone-black thus discharged falls into a receiving-chamber, *D*, which has an inclined bottom, *d*, by means of which the exhausted bone-black is conducted by its own 15 gravity into the bottom of the well *E*, from which it is elevated by means of the bucket-and-chain elevator *F*, and is discharged at the mouth of the well upon the inclined chute *f*.

The saccharine liquor to be decolorized is introduced into the well by means of the pipe *G* from a suitably-elevated cistern, *G'*. The sugar-liquor thus introduced falls into the 20 bottom of the well, and rises by hydrostatic pressure through the mass of bone-black *B* contained in the filtering-chamber, and is discharged therefrom, by means of the system of transverse draining-troughs *H* through the 25 perforations *H'* in the side wall of the cylinder *A*, into the external annular trough, *H²*, surrounding the cylinder *A*, from which it is conducted off by the discharge-pipe *H³*. Each of the troughs *h* of the system of troughs is 30 either covered a short distance from both of its ends or is connected with a short tube, *h'*, the outer end of which is inserted in one of the perforations *H'* in the wall of the cylinder *A*. The superincumbent mass *b'* of bone-black 35 is prevented from falling into the drain-troughs *h* by the inverted-V-shaped shields *I*. As will be seen, each one of the troughs *h* is provided with one of the shields *I*, the wings *i i* of which extend a suitable distance below the edge of 40 the top of the trough.

If required, wire-gauze sieves *k k* may be fastened in the spaces between the troughs and the inner sides of the wings *i i* of the shields, as shown in Fig. 5, or a single sieve, *K*, may 45 be attached at its edges to the wings *i i* of the shields, and may extend across under the trough *H*, as shown in Fig. 6. The object of the sieves is to prevent fine particles of bone-black from being floated up into the troughs. 50 By this mode of organization the resistance to the upward movement of the sugar-liquor through the exterior, as well as the central portion of the mass of bone-black, is rendered as nearly as possible uniform.

55 The compression of the mass of bone-black through which the sugar-liquor is filtered may be effected, as shown in Fig. 1, merely by the weight of the superincumbent mass *b'* of the column of bone-black; or, if desired, compression may be produced by means of the compressor *L*, the rim *L'* of which is supported in the circumferential enlargement *A'* of the cyl-

inder *A*, and has formed upon its face suitable teeth, *L²*, for engagement by the horizontal worm *M*, by means of which the compressor 70 is rotated. The compressor *L* is composed of the rim *L'*, and of radially-arranged suitably-winding blades *l l*, &c., like the blades of a propeller. The inner ends of the blades *l* are attached to a central hub, *L³*, and their outer 75 ends to the interior surface of the rim *L'*. The sugar-liquor makes its way upward through the spaces between the blades *l l*, &c., and thence finds its way into the draining-troughs *h h*, &c., which are arranged just above the 80 compressor, as shown in Fig. 3.

As an additional precaution, to secure the uniform and suitably-slow movement of the sugar-liquor through the bone-black, we introduce it into the apparatus from a cistern, *G'*, 85 which is supplied from the main reservoir through a supply-pipe, *G²*, provided with a ball-cock, *g*, and adjusting devices, by means of which the surface of the sugar-liquor in the cistern is maintained at a level just sufficiently 90 far above the level of the outlet or outlets through which the sugar-liquor escapes from the filtering-chamber to compensate for the frictional resistance which the sugar-liquor meets with in passing down the well and upward through the mass of bone-black in the filtering-chamber to its point of discharge 95 therefrom.

The desired adjustment may easily be obtained by making the float *g²* vertically adjustable relatively to the free end of the lever or arm *g'*, by means of which the valve *g* is operated. Thus the float *g²* may be affixed to the lower end of a stem, *g³*, which is loosely inserted through a sleeve, *g⁴*, provided with a 100 set-screw, *g⁵*, for clamping the stem *g³* in the position in which it may be adjusted. The sleeve *g⁴* is provided with a horizontal pivotal connection, *g⁶*, with the free end of the valve-operating arm *g'*.

The valve *g* is capable of supplying the cistern with a larger quantity of liquor than is required, and therefore by varying the height of the float *g²* relatively to the end of the arm *g'*, with which it is connected, the height of the sugar-liquor in the cistern may be correspondingly varied. It will of course be understood that the draining-troughs *h* and their shields need not necessarily be parallel with each other, nor necessarily independent of each 115 other, so long as they are so arranged as to drain the sugar-liquor from the column of bone-black at a prescribed level.

We claim as our invention—

1. In an apparatus for decolorizing sugar-liquor 120 by the process of upward filtration through a column of bone-black contained in a suitable vessel or cylinder, a system of draining-troughs extending transversely into or across the column of bone-black at the height at which 130 it is desired to drain the sugar-liquor therefrom, and a system of shields over the draining-troughs for preventing the bone-black from falling into the said troughs, and a con-

duit or conduits for receiving and conducting off the sugar-liquor discharged through the draining-troughs.

2. The draining-troughs *h h*, &c., extending 5 transversely into or across the column of bone-black at the desired height, and the shields *II*, &c., each having the flaring sides or wings *ii*, as and for the purposes set forth.

3. The draining-troughs *h h*, &c., and the 10 shields *II*, &c., each provided with a sieve for preventing particles of bone-black from being floated upward into the said troughs by the rising of the sugar-liquor through the column of bone-black, into or across which the 15 draining-troughs extend.

4. A system of draining-troughs provided 20 with suitable shields and arranged transversely across a column of bone-black contained in a filtering-cylinder and connected by comparatively short tubes with perforations 25 in the wall of the filtering-cylinder leading to a conduit or conduits for receiving and conducting off the sugar-liquor drained from the column of bone-black, for the purpose of increasing the facility of drainage from the 30 interior portion of the column of bone-black, and diminishing the facility of drainage from the exterior portion thereof, and thereby rendering the upward current of sugar-liquor through all parts of the column of bone-black as nearly uniform as may be.

5. In combination with filtering apparatus for decolorizing sugar-liquor by the process of upward filtration through bone-black, substantially such as described, a cistern for supplying sugar-liquor to the apparatus, suitably elevated, and provided with means for adjusting the height of the sugar-liquor in the said cistern relatively to the height of the outlets through which the sugar-liquor is discharged 35 from the filtering-chamber, substantially as described.

6. The filtering-cylinder *A*, provided at a prescribed elevation with discharge-outlets *H'*, for the discharge of the sugar-liquor after 40 filtration, in combination with a cistern, *G'*, and a suitable connection therefrom to the lower part of the cylinder *A*, the supply-pipe *G²*, the valve *g*, provided with the operating-arm *g'*, and the vertically-adjustable float *g²*, 45 connected with the free end of the arm *g'*, and means for vertically adjusting the float *g²* relatively to the said arm, as and for the purpose set forth.
